HARVEY A. MOYER, OF SYRACUSE, NEW YORK.

TYPE-WRITING MACHINE.

No. 820,935.

Specification of Letters Patent.

Patented May 15, 1906.

Application filed March 15, 1905. Serial No. 250,245.

To all whom it may concern:

Be it known that I, HARVEY A. MOYER, of Syracuse, in the county of Onondaga, in the State of New York, have invented new and useful Improvements in Type-Writing Machines, of which the following, taken in connection with the accompanying drawings, is a full, clear, and exact description.

This invention relates to certain improvements in type-writing machines of the class commonly known as "front-strike" or "visible-writing" machines, and refers more particularly to the type-bar action. In this class of machines the type-bars are pivotally hung in a substantially vertical arc and are each provided with lower and upper case characters adapted to be brought to the same printing-point at the front of a suitable platen.

In my present machine each type-bar action comprises a key-lever, an intermediary lever fulcrumed at its lower end separate from the key-lever and having its upper end linked to the heel of the type-bar, and an equalizing draw-bar connecting the intermediate portion of the intermediary lever directly to the key-lever.

The lower ends of the intermediary levers are mounted side by side upon the same horizontal fixed axis or fulcrum, and their upper ends are disposed in an arc concentric with the arc in which the type-bars are pivoted, and therefore these intermediary levers gradually increase in length from the center toward the ends of the arc.

The primary object of this construction is to obtain a simple, quick, and easy action of the type-bar with a comparatively light stroke of the key-lever.

Another object of equal importance is to enable each draw-bar to be adjusted to a nicety, according to the length of its intermediary lever, to produce the same travel or throw of the type-bars with a uniform degree of pressure upon and movement of the key-levers.

A further object is to bring the key-levers and intermediary levers into such relative convergence that the collective transverse widths at the points of connection of the draw-bars with the intermediary and key levers is substantially equal, whereby the draw-bars are caused to travel in substantially parallel vertical planes, while the intermediary levers swing in converging planes.

A still further object is to converge the key-levers in straight lines from their keys to their

fulcrums and to dispose the fulcrums in an arc of a circle having its center at the point of convergence of the lines of the key-levers, so that each fulcrum is disposed at right angles to all parts of the key-lever, and thereby obviates any lateral or torsional strain in the key-lever action.

Other objects and uses will be brought out in the following description.

In the drawings, Figure 1 is a horizontal sectional view of a portion of a front-strike writing-machine, showing in top plan my improved system of key-levers and a portion of the system of type-bars and their connection with their respective key-levers and also showing a portion of a type-bar segment and its shifting mechanism. Fig. 2 is a transverse vertical sectional view taken on line 2-2, Fig. 1, looking toward the front of the machine. Fig. 3 is a longitudinal vertical sectional view through the center of the machine, showing the central and extreme end type-bars and their actuating key-levers, the end type-bar being shown in its printing position. Fig. 4 is a view similar to Fig. 3, except that the intermediary levers and draw-bars are connected to draw forwardly instead of rearwardly.

In carrying out the objects stated a series of straight rearwardly-converging key-levers 1 are symmetrically arranged side by side within the base of a substantially rectangular frame A and are fulcrumed at their rear ends in a horizontal circular segment 2, having its center at the point of convergence of the lines of the key-levers, so that each fulcrum is disposed at right angles to its key-lever and allows a free vertical movement of the individual keys without liability of lateral rocking or torsional strains. These several key-levers are therefore fulcrumed at their rear ends in a horizontal circular arc and radiate forwardly from said arc in straight diverging lines and in substantially the same horizontal plane, and their front ends terminate in substantially straight transverse rows and are equipped with suitable finger-keys in straight transverse rows, which are stepped in the usual manner for single keyboards and bear the usual double-case characters.

A corresponding number of type-bars 3 are pivoted at 4 in a substantially vertical circular arc above the key-levers 1 to cause their type to strike upwardly and rearwardly at one and the same printing-point and against the front side of a superimposed platen 5. These type-

bars are normally disposed in a substantially horizontal position with their front ends resting on a suitable circular seat 6 and their rear ends fulcrumed in a substantially vertical circular segment 7 and connected by links 8 to a system of intermediary levers 9 of the third order, which in turn are connected to their respective key-levers by a system of equalizing draw-bars 10, all of which parts are so relatively arranged as to afford ample clearance for the free movement of each individual type-bar action without friction or interference one with the other and to enable each type-bar to be thrown to the printing position with the same uniform degree of pressure and movement of the key-lever.

In order to carry out this purpose, the lower ends of the intermediary levers 9 are fulcrumed side by side upon the same fixed horizontal axis or bar 11, running transversely of and directly above the key-levers 1, and are spaced apart a sufficient distance to afford ample clearance and in such manner that the collective width of the lower-ends of the intermediary levers is substantially equal to the collective width of the key-levers in a line directly beneath the axis of said intermediary levers, such transverse width being greater than the chord of the arc in which the type-bars are pivoted. This arrangement brings the lower ends of the intermediary levers directly above their respective key-levers and at substantially right angles to their axis; but from this point substantially all the intermediary levers converge upwardly at the rear of the type-bar pivots, as best seen in Fig. 2, at such an angle as will bring both ends of each draw-bar in substantially the same longitudinal vertical plane, so that the draw-bars pull in nearly parallel lines. (See Fig. 2.)

The upper extremities of the lever 9 terminate in an arc slightly above and substantially parallel with the arc in which the type-bars are pivoted and are offset at m radially of said arc and in the swinging plane of their respective type-bars, and the links 8 are pivoted to their respective type-bars and to said radially-deflected ends of the levers 9 in arcs which are also substantially parallel with the arc in which the type-bars are pivoted, so that each link 8 travels in the same plane as its type-bar without cramping or twisting its pivotal ends.

In like manner the lower ends of the levers 9 at n are disposed at right angles to their axis and swing freely without cramping or twisting in their bearings, and this, together with the radial upper extremities swinging in the plane of movement of the type-bars, renders the type-bar action exceedingly easy and responsive to the touch on the keys and adds materially to the permanency of alignment and durability of the machine.

It is also clear that by pivoting these levers 9 on the same horizontal axis and terminat-

ing the upper ends in an arc substantially parallel with the arc in which the type-bars are pivoted the levers 9 gradually increase in length from the center toward the ends of the arc, and therefore those of different length require a different degree of movement to throw their type-bars through equal arcs from their normal to their printing positions—that is, the free ends of the levers 9 travel substantially the same distance, but the angle through which the longer levers move is less than that through which the shorter levers travel.

Now one of the main objects which I have sought to carry out is to connect these various lengths of intermediary levers to their respective key-levers in such manner that each type-bar is brought to its printing position by the same uniform degree of pressure and stroke of its key-lever and to make this stroke and pressure as light as practicable. In other words, I have not only sought to equalize, but to reduce, the leverage between the key-levers and type-bars through the medium of the equalizing draw-bars 10 and their particular system of connections with the key-levers 1 and intermediary levers 9. This is best accomplished, as seen in Figs. 1 to 3, inclusive, by pivotally connecting the upper ends of the draw-bars 10 to the intermediary levers 9 at the same distance above the fulcrum 11 and their lower ends to the corresponding key-levers 1 at different distances at the rear of said fulcrum, but in front of the fulcrum of the key-levers, in such manner as to substantially equalize the leverage, so that the equalizing draw-bars incline downwardly and rearwardly in substantially straight lines and in practically parallel longitudinal vertical planes from the intermediary to the key levers and operate to rock the intermediary levers 9 rearwardly when the key-levers are depressed to throw the type-bars to their printing positions.

It will be observed that the longer intermediary levers 9 require less movement, but greater power, to throw their type-bars to the printing position than the shorter ones, and in order to compensate for this inequality in the movement and power the equalizing draw-bars for the longer levers are connected to their key-levers at gradually-increasing distances from the keys and also from the fulcrum-bar 11—that is, the key leverage is gradually increased from the center toward the sides as the length of the intermediary levers 9 increases. This arrangement enables each type-bar to be thrown to the printing position with a comparatively slight depression of and with the same uniform power or touch upon the key, thereby establishing an easy and speedy type-bar action.

The relative convergence of the key-levers and intermediary levers is such that the collective transverse widths of each system of levers at the points of connection of the equal-

izing draw-bars are substantially equal and cause said draw-bars to act upon the intermediary levers in substantially vertical longitudinal planes, as best seen in Fig. 2, while 5 the intermediary levers swing in upwardly converging planes.

It will be seen that by pivotally attaching each draw-bar to its intermediary and key lever in the manner described only a very 10 slight movement of the key-lever is required to throw the type-bar through its full arc of movement and that, owing to this fact, the action of the type-bar is almost instantaneous with the first touch of the key, thereby obviating the necessity for any special devices for 15 producing the usual "sliding" motion, such as "slotted" type-bars and "cams" and other "differential-leverage" devices, which are always difficult to make and add materially to the cost of production and necessary 20 repairs of the machine.

In Fig. 4 I have shown the intermediary levers 9 as linked to their type-bars below their type-bar pivots, while the equalizing 25 draw-bars are connected to their respective intermediary and key levers in front instead of at the rear of the fulcrums 11, so that as the key-lever is depressed the intermediary levers are rocked forwardly to throw the 30 type-bars to their printing position. In this case the power and key-stroke equalizing effect is produced by connecting the equalizing draw-bars at different distances from the fulcrums of both the intermediary and key 35 levers; otherwise the advantages are substantially the same as those described for the constructions seen in Figs. 1 to 3, inclusive.

In this class of machines the type-bars are usually equipped with plural characters, or 40 lower and upper case type, and therefore it becomes necessary to shift either the type-bars or platen to cause the type of either case 45 to print at one and the same point.

In order to show a complete operative device, so far as the type-bar action is concerned, I have shown said type-bars as pivoted to a vertically - shiftable segment 7, which is carried upon the inner ends of a U- 50 shape lever-frame 21 and is further supported by suitable bracing-arms 22.

The segment 20 preferably consists of two opposed similar segmental plates both cut from the same ring and secured together face to face by suitable fastening means, as screws 55 23, each plate having a circular groove, each registered with the other and receiving the pivots of the type-bars 3, while the complete segment is slotted transversely to receive said type-bars and sustain them against 60 due axial movement.

The pivots of the type-bars preferably consist of a wire upon which the type-bars are threaded, and the wire, with the type-bars thereon, is then clamped in the circular 65 groove between the plates, the advantage of

this being to facilitate the manufacture of the segment.

Secured to the ends of the segment are depending brackets 25, to the lower ends of which the inner ends of the lever 21 are pivoted. This lever 21 is fulcrumed at 26 to the opposite sides of the frame A of the machine, and its front end is provided with suitable shift-keys 20, by which the lever-frame 21 may be operated to shift the segment vertically. 70 75

The bracing-arms 23 are pivoted at their rear ends to the opposite sides of the main frame A, and their front ends are pivoted to the upper ends of the brackets 25 and serve 80 to steady the segment 7 in its vertically-shifting movement.

It is to be further understood, however, that I do not limit myself to any particular form of segment and that I reserve the right 85 to use any means for shifting either the segment or platen.

The particular form of shifting mechanism herein shown and particularly described is equally applicable for shifting the platen, and 90 I contemplate filing a separate application upon a shifting mechanism embodying essentially the features herein shown and described.

The operation of my invention is fully incorporated in the foregoing description, which 95 is deemed sufficiently clear and exact to enable any one skilled in the art to construct and operate the machine, and it is clearly evident that some change may be made in adapting the type-bar action to a platen-shift machine without departing from the spirit of my invention—as, for instance, the upper end of the intermediary levers may be connected directly to the heel of the type-bar and other minor changes may be made to 105 conform to different styles of segments and type-bars.

Having thus described my invention, what I claim, and desire to secure by Letters Patent, is—

1. In a front-strike type-writing machine, a series of type-bars pivoted in a circular arc to strike at the same printing-point, in combination with a system of key-levers converging rearwardly from their keys in straight 115 lines and fulcrumed at their rear ends in a horizontal arc struck from the point of convergence of said lines, a system of upwardly-converging intermediary levers fulcrumed at their lower ends in a straight line transversely 120 of the key-levers and having their upper ends disposed in an arc and connected to the type-bars, and a system of equalizing draw-bars attached to the intermediary levers above 125 their fulcrums and to the key-levers at one side of their fulcrums, said draw-bars being attached to one system of levers at different points in their lengths to equalize the power and degree of movement necessary to throw the type-bars to the printing position. 130

2. In a front-strike type-writing machine, the combination with a system of type-bars, of a system of key-levers converging rearwardly in straight lines from points directly below their keys to their fulcrums, and fulcrumed at their rear ends, upwardly-converging intermediary levers fulcrumed at their lower ends and having their upper ends connected to the type-bars, and connections whereby motion is transmitted from the key-levers to their respective intermediary levers to actuate the type-bar.

3. In a front-strike type-writing machine, the combination with a system of type-bars, of a system of key-levers converging rearwardly in straight lines from points directly below their keys to their fulcrums and fulcrumed at their rear ends, upwardly-converging intermediary levers fulcrumed at their lower ends and having their upper ends connected to the type-bars, and draw-bars attached directly to the key-levers and to their corresponding intermediary levers.

4. In a front-strike type-writing machine, the combination with a system of type-bars, of a system of key-levers converging rearwardly from their keys in straight lines and fulcrumed at their rear ends, upwardly-converging intermediary levers fulcrumed at their lower ends and having their upper ends connected to the type-bars, and draw-bars connected to said levers at such points as will cause each type-bar to move through an equal arc by an equal depression of each key-lever.

5. In combination with a platen, a series of type-bars pivoted in an arc to strike at the same printing-point, a series of upwardly-converging intermediary levers fulcrumed on a common axis below the type-bars and having their upper ends disposed in an arc and each linked to one of the type-bars, horizontal key-levers, equalizing draw-bars each having its upper end pivoted directly to one of the first-named levers at a point above its fulcrum and its lower end pivoted directly to the key-lever.

6. In a front-strike type-writing machine, the combination with a platen, pivoted type-bars and horizontal key-levers, of upwardly-converging intermediary levers fulcrumed on a common axis above the key-levers and below the type-bars and having their free ends connected to their respective type-bars, and equalizing draw-bars each having its lower end pivoted to the key-lever and its upper end pivotally attached directly to one of the intermediary levers between its fulcrum and connection with the type-bar.

7. In a front-strike type-writing machine, a system of type-levers pivoted in a vertical arc, a system of key-levers having their fulcrums arranged in a horizontal arc, said key-levers extending forwardly from their fulcrums in straight lines radial to said horizon-

tal arc, a system of upright intermediary levers having their fulcrums disposed in a straight line transversely of the key-levers, said intermediary levers gradually increasing in length from the center toward the side of the machine and converging upwardly from their fulcrums, links connecting the upper ends of said levers with their respective type-levers and a system of equalizing draw-bars each pivotally connected to one of the key-levers and to the intermediary levers in transverse lines where the collective width of the key-levers is substantially equal to the collective width of the intermediary levers.

8. In a front-strike type-writing machine, the combination with a platen, of type-levers fulcrumed in the arc of a circle having its center at the printing-point, upwardly-converging intermediary levers fulcrumed on a fixed common axis below the type-levers and gradually increasing in lengths from the center toward the ends of the arc, said intermediary levers having their upper ends connected to their respective type-levers, and key-levers converging rearwardly from their keys in straight lines from points directly below their keys to their fulcrums and connected to the upright levers above their fulcrums.

9. In a front-strike type-writing machine, the combination with a series of type-levers and key-levers, of a corresponding series of upwardly-converging intermediate levers fulcrumed on a fixed common axis below the type-levers and connected to their respective type-levers, and equalizing draw-bars connected at different lengthwise points to the key-levers and attached to the intermediary levers above their fulcrums.

10. In a type-writing machine, the combination with a platen and type-bars pivoted in a circular arc to strike the front face of the platen, of a system of operating devices for the type-bars, each device including a key-lever, an upright intermediary lever, and an equalizing draw-bar, said intermediary lever and draw-bar converging upwardly from the key-lever and pivotally attached at their points of convergence, each intermediary lever being linked to its type-bar above its connection with its draw-bar, and the draw-bar having its lower end pivotally attached to the key-lever.

11. In a front-strike type-writing machine, a series of type-bars pivoted in a circular arc, a series of upwardly-converging intermediary levers pivoted at their lower ends in the same horizontal line and gradually increasing in length from the center toward the ends of the arc, the upper ends being in planes radial to such arc, links connecting the upper ends of the intermediary levers to their respective type-bars, key-levers, one for each type-bar, and equalizing draw-bars extending upwardly from and pivotally attached to the key-levers and having their upper ends piv-

oted to their respective intermediate levers above the fulcrums of said intermediate levers.

12. The combination with a platen, type-bars and key-levers of a front-strike type-writing machine, of upwardly-converging intermediate levers pivoted at their lower ends in the same horizontal line and having their upper ends linked to their respective type-bars, and equalizing draw-bars of different lengths connecting the intermediate levers with their key-levers.

13. In a type-writing machine, the combination with a platen, of a plurality of type-bars pivoted in an arc to strike at the same printing-point at the front side of the platen, upwardly-converging intermediary levers fulcrumed at their lower ends and having their upper ends radial to said arc and connected to the type-bars, key-levers converging rearwardly from their keys in straight vertical planes, and equalizing draw-bars attached directly to the intermediary and key levers.

14. The combination with the platen and type-bars of a front-strike type-writing machine, of a system of rearwardly-converging key-levers, and a system of upwardly-converging intermediate levers, draw-bars pivoted to the key-levers and to the intermediate levers, the collective width of the key-levers at their points of connection with the draw-bars being substantially equal to the collective width of the intermediate levers at their point of connection with said draw-bars.

15. The combination with the platen and type-bars of a front-strike type-writing machine, of a system of rearwardly-converging key-levers, a system of upwardly-converging intermediate levers fulcrumed at their lower ends on the same horizontal axis above and transversely of the key-levers and their upper ends connected to the type-bars, and equalizing draw-bars connecting the intermediary to the key levers, the collective transverse width of the key-levers at their points of connection with the draw-bars being substantially equal to the collective transverse width of the intermediary levers at their points of connection with said draw-bars.

16. In a type-writing machine, a series of type-bars pivoted in a circular arc, in combination with upwardly-converging intermediate levers fulcrumed at their lower ends and all having their upper ends disposed in planes radial to said arc and connected to the type-bars, and a system of key-levers each connected to its intermediary lever.

17. The combination with a series of type-bars pivoted in an arc to strike at one and the same printing-point, of a system of key-levers, intermediary levers fulcrumed at their lower ends on the same horizontal axis and at right angles thereto, and having their upper ends disposed in planes radial to said arc and

connected to the type-bars, and draw-bars connected to the intermediary and key levers at such points as will move the upper ends of the intermediary levers equal distances by substantially the same stroke of 7c the key-levers.

18. The combination with a platen and a series of type-bars pivoted in an arc to strike at the same printing-point at the front side of the platen, of a system of key-levers converging rearwardly in straight lines from their keys and having their front ends terminating in straight transverse rows and their rear ends engaging fulcrums which are arranged in a horizontal arc, each key-lever having 8c suitable connection with its type-bar to throw the latter to its printing position.

19. In combination with a platen and a series of type-bars pivoted in an arc to strike at the same printing-point at the front side of the 85 platen, of a system of key-levers converging rearwardly in straight lines from their keys and having their front ends terminating in straight transverse rows and their rear ends engaging fulcrums which are arranged in a 90 horizontal arc, and intermediate levers fulcrumed at their lower ends and each connected to one of the type-bars and to its corresponding key-lever.

20. The combination with a platen and a 95 series of type-bars pivoted in an arc to strike at the same printing-point at the front side of the platen, of a system of key-levers converging rearwardly in straight lines from their keys and having their front ends terminating in straight transverse rows and their rear ends engaging fulcrums which are arranged in a horizontal arc, intermediary levers fulcrumed at their lower ends and having their upper ends connected to the type-bars and equalizing draw-bars each connected to one of said intermediary levers and to its corresponding key-lever. 100 105

21. The combination with a platen and a series of type-bars pivoted in an arc to strike at the same printing-point at the front side of the platen, of a system of key-levers converging rearwardly in straight vertical planes from their keys, and having their front ends terminating in straight transverse rows and their rear ends fulcrumed in a transverse line, upwardly-converging intermediary levers fulcrumed at their lower ends and having their upper ends connected to the type-bars, and equalizing draw-bars connected to 110 115 their respective intermediary levers and key-levers.

22. The combination with a platen and a series of type-bars pivoted in an arc to strike at the same printing-point at the front side 125 of the platen, of a system of key-levers converging rearwardly in straight lines from their keys, and having their front ends terminating in straight transverse rows and their rear ends engaging fulcrums which are ar- 130

ranged in a horizontal arc, upwardly-converging intermediary levers fulcrumed at their lower ends on a fixed horizontal axis and having their upper ends disposed in planes radial to the arc in which the type-bars are pivoted and connected to said type-bars, and draw-bars connecting said intermediary levers to their respective key-levers.

23. In a type-writing machine, the combination with a platen and type-bars pivoted in an arc to strike at the same printing-point, of a system of rearwardly-converging key-levers, a system of upwardly-converging intermediary levers, and draw-bars pivotally connected to the intermediary levers and to the key-levers, the collective width of the key-levers at their points of connection with the draw-bars being substantially equal to the collective transverse width of the intermediary levers at their points of connection with said draw-bars.

24. In a type-writing machine, the combination with a platen and type-bars pivoted in a substantially vertical arc, of a system of key-levers fulcrumed in a substantially horizontal arc, intermediary levers fulcrumed at their lower ends on a horizontal axis and having their upper ends disposed in a vertical arc and connected to the type-bars, and draw-bars connected to the levers in such manner as to equalize the stroke of the several key-levers in throwing the type-bars to the printing position.

25. In a front-strike type-writing machine, a type-bar and a key-lever, the latter fulcrumed at its rear end in combination with an upright rock-arm linked to the heel of the

type-bar, and a draw-bar attached to the rock-arm and also pivotally attached to the key-lever in the plane of a direct line drawn between the fulcrum and key of the key-lever.

26. In a type-writing machine a series of type-bars pivoted in the arc of a circle to strike upwardly and rearwardly, a system of upwardly-converging rock-levers, each linked to one of the type-bars, a system of key-levers converging rearwardly in straight vertical planes from their keys to their fulcrums, and a system of equalizing draw-bars arranged in parallel vertical planes running from front to rear and each connecting one of the rock-levers to one of the key-levers.

27. In a front-strike type-writing machine, a system of type-bars pivoted in a circular arc, a system of key-levers converging rearwardly in straight vertical planes from their keys to their fulcrums, a system of intermediary levers having their lower ends disposed in parallel vertical planes and pivoted upon a common axis, and their upper ends disposed in planes substantially parallel with the swinging planes of their respective type-bars and connected to said type-bars, and a system of draw-bars of varying lengths from the center toward the side of the machine, each of said draw-bars connecting one of the intermediary to one of the key levers.

In witness whereof I have hereunto set my hand this 11th day of March, 1905.

HARVEY A. MOYER.
